Inventor:
John P. Carroll,
By Glenn S. Noble
Atty.

UNITED STATES PATENT OFFICE.

JOHN P. CARROLL, OF CHICAGO, ILLINOIS.

TRENCH SUPPORTING.

Application filed June 8, 1925. Serial No. 35,712.

To all whom it may concern:

Be it known that I, JOHN P. CARROLL, a citizen of the United States, residing at Chicago, in the county of Cook and State 5 of Illinois, have invented certain new and useful Improvements in Trench Supporting, of which the following is a specification.

In digging trenches for building deep supporting walls for basements or the like, 10 it has heretofore been a more or less common practice to dig the trench somewhat wider than the wall to be built therein, and shoring the sides of the trench and supporting the same by means of jacks or drums 15 and then putting in the form for one side of the wall, the form for the other side comprising the timbering on the side of the trench. When the forms had been completed, concrete would be poured into the 20 bottom of the forms and allowed to set, then the first series of drums or jacks would be removed and more concrete poured into the forms and allowed to set and this process repeated until the forms were filled. The 25 layers of concrete would be approximately three feet in depth and would require considerable time, often several days, to set before the next layer could be placed in position. On account of this intermittent filling, this would necessitate considerable time 30 in order to properly fill the forms or complete the wall, as well as involving expense in removing the jacks and other props from the forms.

35 In accordance with the present invention I provide a novel method of wall construction and trench supporting which will avoid the objections above noted and also provide novel means for carrying out such new method of wall construction.

The objects of this invention are to provide an improved method of trench supporting and wall construction, together with means for carrying out such method; to provide means whereby the forms for a deep wall which is being formed in a trench may be entirely filled at one operation or without waiting for the setting of the concrete in the wall; to provide a novel brace and drum 45 or jack for trench supporting; and to provide such other novel features as will be described more fully hereinafter.

In the accompanying drawings illustrating this invention,

50 Figure 1 is a vertical sectional view show-

ing the bottom of a trench with my improved form of construction therein;

Figure 2 is an enlarged sectional view taken on the line 2-2 of Figure 1;

Figure 3 is a section taken on the line 60 3-3 of Figure 1;

Figures 4 and 5 are details showing a modified form of brace; and

Figure 6 shows the apparatus as arranged for a basement wall or wall around an open 65 excavation instead of a trench.

Figure 1 shows the lower portion of a trench 7 having sides 8 and 9 and bottom 10. The sides 8 and 9 are provided respectively with planking or sheathing 11 and 12 for supporting the same during the excavation and while the wall is being constructed, it being understood that the trench referred to is dug in material in which the walls are not self-supporting.

75 The planks or sheathing are preferably arranged vertically and are braced against the walls or further supported by means of additional timbering or beams and suitable jacks or the like. In the arrangement shown, I provide horizontal beams 13 for engagement with the planks or sheathing 11. Such beams may be made of wood or fabricated from iron, as shown. In place of ordinary drums or jacks, I provide struts 80 or braces 14 which are approximately as long as the width of the wall which is to be constructed. These struts or braces may be made in any suitable manner, but preferably comprise longitudinal channels 15 85 which are connected by lattice work 16. A plate or short section of channel 17 is arranged a short distance from one end to engage with the beam 13, which is straddled by the upper and lower channel sections. 90 Another plate or short section of channel 18 is arranged at a short distance from the opposite end of the strut, thereby forming a socket or recess for receiving one end of a drum or brace 19, forming a part of a 100 jack or screw compression member 20, which may be formed in any ordinary or preferred manner. For instance as shown, the drum 19 has a cap 21 which is threaded to receive a screw 22, having a head 23 for 105 turning the same. The opposite end of the screw engages with a plate or stationary member 24 which rests against beams 25 which are pressed against the planks or sheathing 12 on the side of the trench. It 110

will be noted that the drum 19 extends into the socket in the strut 14 a sufficient distance to keep these parts in alignment while the apparatus is being installed, and holding the sides of the trench apart. It will be understood that any number of such struts and jacks may be used in connection with each set of beams 13 and 25, and similar supporting apparatus may be arranged at various intervals throughout the height of the trench, depending upon the nature of the soil.

When the trench has been completed and all of the supporting apparatus is placed in position, a form 26 is constructed at a proper distance from the side of the trench 8 for supporting the opposite side of the wall 27 which is to be formed by pouring concrete into the space between these side forms. The form 26 may be made in any suitable manner and may be supported from the side 9 by means of braces 28 or the like. The form 26 is preferably placed so that the inner surface will be in alignment with the face of the plates 18. When the form for the wall is thus completed, the concrete may be poured therein until the entire form is filled so that the wall may be completed in substantially one operation or without waiting for any portion of the concrete therein to set. It will be noted that as the concrete is poured into the form it will enclose the beams 13 and brace 14 which will be completely embedded in the same, and as these are fabricated from iron or steel, they will serve as reinforcements for the concrete. As soon as the concrete has set, the jacks 20 and the forms 26 may be removed. Such jacks will ordinarily be removed gradually from the bottom toward the top of the trench and as the jacks are taken out, the projecting ends of the struts 14 are burned off or cut away, leaving the plates 18 flush with the face of the wall 27.

It will also be noted that the form 26 may be arranged at the ends of the struts 14 as indicated by dotted lines. In such case, the sockets for the drums 19 should be enclosed to prevent the concrete from coming in contact therewith. As the drums are removed in this instance, the sockets may be filled with concrete if considered necessary.

In the arrangement shown in figure 6 where the wall is to be constructed around an open excavation as for instance around the sides of a basement, the outer basement wall 29 is supported by sheathing or lagging 30 having longitudinal beams 13 and struts 14 as above described, but in this instance, the braces 19 are made sufficiently long so that the jacks 20 may engage with posts or abutments 31 at the bottom of the basement. The inner form member 26 is arranged in a similar manner to the one above described and is supported in any conven-

ient and well known way, otherwise the arrangement and operation is substantially the same as with the apparatus above set forth.

In some instances the struts or compression members instead of being fabricated from steel shapes may be made of cast iron as shown at 32 in figures 4 and 5. In this instance, the socket 33 is cast directly in the end for receiving the drum or brace 19. These struts are also preferably made hollow and provided with openings 34 for allowing the concrete to completely embed the same.

From this description it will be seen that I provide means whereby walls may be more expeditiously constructed in trenches or the like than with the usual method heretofore employed, and the struts and beams or compression members not only serve in the process of construction but also serve to reinforce the completed wall. It will be noted that the method may be modified and the parts used may be changed in order to adapt the invention to various conditions such as are found in construction work, and therefore I do not wish to be limited to the exact method or means heretofore described, except as specified in the following claims, in which I claim:

1. The method of constructing a trench and wall therein, which consists in digging the trench and supporting the sides by means of suitable sheathing and two-part shoring members, then making a form which will enclose one part of each shoring members, then filling the form with concrete, thereby embedding such parts of the shoring members therein, and finally removing the other portions of the shoring members and the removable portions of the wall supports and forms.

2. The method of forming a trench with a wall therein, which consists in digging the trench, placing side supports comprising sheathing and longitudinal beams, with struts to engage with the beams on one side of the trench and coacting with jacks which engage with the beams on the opposite side of the trench, then constructing a form to enclose a portion or all of each of said struts, filling the form with concrete to complete the wall, and finally withdrawing the jacks and removing all or a portion of the forms and wall supports, substantially as described.

3. The herein described method of construction, which consists in digging a trench and sheathing the sides thereof, holding the sides apart by means of longitudinal beams and transverse struts, said struts having sockets in the end for receiving drums, screw jacks engaging with the drums and with the beams on the opposite side of the trench, placing a form adjacent to the ends of the struts, then filling the space between the

form and the opposed sheathing with concrete, thereby embedding the main portions of the struts, then removing the jacks and drums and cutting off any projecting ends of the struts, and finally removing the forms and sheathing, substantially as described.

4. Trench supporting apparatus comprising sheathing for engagement with the sides of the trench, longitudinal beams engaging with said sheathing, transverse struts engaging with the beams on one side of the trench, jacks coacting with said struts and engaging with the beams on the opposite side of the trench, said struts being formed of metal and being adapted to be left in the concrete when it is poured into place to form a wall in the trench.

5. Trench supporting apparatus comprising suitable lagging for the sides of the trench, beams engaging with said lagging, struts engaging with the beams on one side of the trench and having sockets in their opposite ends, drums engaging with said sockets, screws engaging with said drums, plates engaging with said screws and the beams on the opposite side of the trench, said struts being formed of suitable material so that they may be left in the wall

which is to be formed in the trench, substantially as described.

6. A supporting member for trenches or the like, comprising a strut formed of metal with openings in the side to permit concrete to pass therein, a socket on the end of said strut, a drum engaging with said socket and adapted to be held in alignment therewith, and a screw jack coacting with the drum.

7. In trench supporting, the combination with the sides of the trench, of suitable lagging, beams engaging with said lagging, struts engaging with the beams on one side of the trench, screw jacks engaging with said struts and with the beams on the opposite sides of the trench and arranged to be held in alignment with the struts, a form positioned adjacent to the inner ends of the struts and adapted to retain concrete between the same and the lagging on one side of the trench, the arrangement being such that when the concrete has been poured and the wall formed, the jacks together with the forms and a portion or all of the lagging may be removed, leaving the struts embedded in the wall.

JOHN P. CARROLL.
